US00D805979S

(12) **United States Design Patent** (10) **Patent No.:** **US D805,979 S**
(45) **Date of Patent:** **** Dec. 26, 2017**

(54) **SIDE MIRROR FOR A MOTOR VEHICLE**

(71) Applicants: **Yutaka Kubota**, Toyota (JP); **Yuji Muro**, Nagoya (JP)

(72) Inventors: **Yutaka Kubota**, Toyota (JP); **Yuji Muro**, Nagoya (JP)

(73) Assignee: **Toyota Jidosha Kabushiki Kaisha**, Toyota-shi, Aichi-ken (JP)

(**) Term: **15 Years**

(21) Appl. No.: **29/561,430**

(22) Filed: **Apr. 15, 2016**

(30) **Foreign Application Priority Data**

Oct. 16, 2015 (JP) 2015-022910

(57) **CLAIM**

The ornamental design for a side mirror for a motor vehicle, as shown and described.

DESCRIPTION

FIG. 1 is a front perspective view of a side mirror for a motor vehicle, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Our design includes a mirror image of the embodiment depicted in FIGS. 1-7.

1 Claim, 7 Drawing Sheets
